UNITED STATES PATENT OFFICE.

GEORGE RINKE, OF DETROIT, MICHIGAN.

SANITARY NAPKIN.

1,107,447.

Specification of Letters Patent. Patented Aug. 18, 1914.

Application filed May 10, 1913. Serial No. 766,815.

To all whom it may concern:

Be it known that I, GEORGE RINKE, a citizen of the United States of America, and resident of Detroit, in the county of Wayne and State of Michigan, have invented 5 certain new and useful Improvements in Sanitary Napkins, of which the following is a specification.

This invention relates to improvements in 10 sanitary napkins, for the use of females during their menstrual periods.

An object of the invention is to produce 15 a device for the use of females during their menstrual period and one which is adapted to be applied to infants as a diaper or as a bandage where an absorbent pad is needed.

A further object of my invention is to 20 provide a device of the character indicated which will have great absorbent capacity and a construction which provides for a disassembling or unfolding of the structure so that it may be hygienically cleansed, which would be difficult and unsatisfactory were the parts associated in fixed relation 25 one to the other.

A further object of the invention is to 30 produce an article of the character noted that will possess advantages in point of efficiency and at the same time provide an article which can be manufactured as a complete article of apparel and one which may be used, when desired, with applied absorbent material placed within a pocket formed in the napkin, all as will be herein- 35 after set forth.

A further object of my invention is to 40 provide a sanitary napkin or pad which is crocheted or knitted to provide a tubular body portion having at opposite ends semi-diametrical extensions of the same length as 45 the tubular body portion, and on the opposite sides of the ends of the tubular body portion from said extensions tabs for attaching the napkin to a belt or support in the usual manner.

In the accompanying drawings which 50 illustrate a preferred embodiment of my invention, Figure 1 is a longitudinal section showing the end extensions housed within the body portion and with the tabs extended. Fig. 2 is also a longitudinal section which shows the end extensions without the body portion, and Fig. 3 is a perspective view of the sanitary napkin.

55 Referring to the drawings 1, denotes the tubular body portion of the article, or men-

strual pad which is preferably made of soft or loosely twisted yarn or fiber having its porous characteristics preserved in order that it will have a maximum absorbent 60 quality, such body portion being formed by knitting or crocheting the yarn or worsted in tubular form so that it may be flattened out for use. A preferred type of yarn used in the make up of the article is cotton yarn 65 made up of a plurality of loosely twisted strands assembled to form an untwisted cord which when knitted will be soft and will leave the capillary qualities of the strands unimpaired, and in knitting a loose 70 stitch is employed which will form longitudinally ribbed or raised portions on both sides with intermediate depressions, and by employing a loose stitch the article will have soft texture and its elasticity will be pre- 75 served.

The tubular body portion 1 of the article has formed thereon or attached thereto tabs 2 and 3, such tabs may be formed of the same material as the part 1, and will be 80 fashioned to be at the ends which join the tubular portion one-half of the length of the circumference thereof and from the point of juncture with the ends of the body portion these tabs have converging edges. 85 The tabs are knit or woven and fashioned to be less elastic than the body portion they being intended to be connected by a safety-pin or other connecting means to straps or bands from a belt or garment to hold the 90 body portion in place upon the person. It will be noted that when the body portion is laid flat that the tabs 2 and 3 project from opposite ends of the same side of the body portion, and it is fully within the purview 95 of my invention to form the tabs independently and then attach them in place, and to affix buttons or their equivalent as straps or elastic bands with loops to the end portions of the tabs.

100 The tubular body portion 1 is constructed to have at the ends thereof flaps 4 and 5, which may be practically about the same length as the length of the body portion, the width of the flaps being about one-half of the circumference of the tubular body portion. When the body portion is laid flat one of the flaps will be a continuation of the body portion, such flap 4 being joined to the body portion at the point of juncture therewith of the tab 3, and the opposite flap 5 is 105 joined to the tubular body portion on the 110

opposite side of its open end from the tab 2. The flaps 4 and 5 may be and are preferably formed as a continuation of the body portion, being knit or woven of the same material and stitch, and in use the flaps are folded or housed within the tubular body portion and in cleansing after use the flaps may be easily withdrawn.

The menstrual pad or napkin herein described may be knit or woven flat with the flaps projecting or extending from opposite sides of the ends and the same end that has the flap 5 may be fashioned to provide the tab 2, the tab 3 being attached when the longitudinal edges of the body portion are joined to form the tubular portion that receives the absorbent flaps.

This sanitary napkin may be used as a diaper for children or infants and when desired other material either absorbent or medicated may be placed within the tubular body portion.

The construction is such that the flaps may be used outside of the tubular body portion if desired. The hygienic characteristics of the device will be apparent and it is obvious that the construction of the same may be varied without departing from the invention set forth in the claims. Though it is within the purview of my invention to make the napkin of ordinary yarn knitted or crocheted with any type of stitch, it is preferred and deemed best to use a stitch which will produce longitudinal ribs between which are depressions, as such a stitch provides a larger absorbent surface than if a flat stitch is used, and the ribs and depressions which alternate will better retain the menses than a flat surface. The yarn used in the make up of the body portion and the flaps or pads is preferably what is known as "candle wick" which is composed of a plurality of strands or threads which are laid together without twisting, and this type of yarn or worsted is well

adapted for the purpose as the absorbent quality of the strands or threads is not impaired by further twisting and said strands are more readily cleansed than twisted yarn.

50

I claim:—

1. A sanitary napkin comprising a tubular body portion, flaps connected to the opposite ends of the body portion and supporting tabs attached to the same side and 55 to opposite ends of the body portion.

2. A sanitary napkin comprising a knitted or crocheted tubular body portion, flaps of the same material and texture as the body portion associated with the opposite ends thereof one to the top and the other to the bottom of the body portion when flat, and tabs connected to the opposite ends of 60 the same longitudinal half of the body portion.

3. As an article of manufacture, a knitted or crocheted sanitary napkin comprising a tubular and openended body portion, flaps which extend from the opposite sides and ends of the body portion which flaps are 70 adapted to be housed one above the other within the body portion and supporting tabs connected to the opposite ends of the same longitudinal half of the body portion.

4. A sanitary napkin comprising a tubular body portion and pads in the form of flat flaps made by crocheting the parts from "candle-wick" yarn using a ribbed stitch the ribs alternating on the same side with depressions and extending longitudinally, 80 and end tabs attached to the body portion one of the tabs being secured to the body portion at the point of juncture of one of the flaps with said body portion.

In testimony whereof, I hereunto affix my 85 signature in the presence of two witnesses.

GEORGE RINKE.
